UNITED STATES PATENT OFFICE.

GARRETT BROWN, OF DENVER, COLORADO.

DESIGN FOR A PINCUSHION.

SPECIFICATION forming part of Design No. 35,578, dated January 14, 1902.

Application filed December 18, 1901. Serial No. 86,429. Term of patent 7 years.

To all whom it may concern:

Be it known that I, GARRETT BROWN, a citizen of the United States of America, residing at Denver, in the county of Arapahoe and State of Colorado, have invented a certain new and original Design for a Pincushion; and I do declare the following to be a full, clear, and exact description of the invention, such as will enable others skilled in the art to which it appertains to make and use the same, reference being had to the accompanying drawings, and to the figures of reference marked thereon, which form a part of this specification.

15 My invention relates to a new and original design for a pincushion.

In the drawings, Figure 1 is a perspective view of a pincushion, showing my new design. Fig. 2 is a cross-section taken through the same on line $x x$, Fig. 1.

As shown in the drawings, the leading or material feature of my design consists of a base having the shape of the frustum of a four-sided pyramid, to the top of which is applied a cushion 6, having a curved exterior surface. In the center of the cushion and at the top of the device is located a circular plate 7.

Having thus described my invention, what I claim, and desire to secure by Letters Patent, is—

The design for a pincushion as herein shown and described.

In testimony whereof I affix my signature in presence of two witnesses.

GARRETT BROWN.
